INVENTOR
George H Parsons
BY Frank W. Ashley
ATTORNEY

UNITED STATES PATENT OFFICE.

GEORGE H. PARSONS, OF NEW YORK, N. Y.

DOLL.

Application filed August 8, 1922. Serial No. 580,411.

To all whom it may concern:

Be it known that GEORGE H. PARSONS, a citizen of the United States, and a resident of New York city, in the county of New York and State of New York, has invented certain new and useful Improvements in Dolls, of which the following is a specification.

My invention relates to dolls, and the object of my invention is to provide a doll with magnets located in the limbs thereof, and especially, in the hands thereof, in such a manner that pieces of ferrous metals may be attracted by the magnets and held thereby in the hands of the doll.

Referring to the drawings, which form a part of this specification:

Figure 1 is an illustrational view of a doll having a magnet embedded in the palm 20 of each hand.

Figure 2 is a cross-sectional view taken on line 2—2 of Figure 1.

A indicates the body of a doll; B—B, respectively, the hands thereof.

In the present case, the doll is shown with limbs formed of plastic material and a small permanently magnetized piece of iron C is embedded in the hands of the doll, preferably in the palms thereof, the plastic being 80 molded around the edges of the metal C and overlapping the same, as indicated at C' in Figure 2, in one plane, and exposed in a plane with the plastic at a plane taken at a right angle thereto, so that a nail or other 35 strip of metal will lay in direct contact with the exposed surface D of the magnet.

If desired, the exposed surface D may be varnished or covered over with a light film of material of the same color as that of the 40 plastic from which the limbs are made, so

that the magnet will not be distinguished from the material in which it is embedded but in any case, it is desirable that the surface of the magnet shall be arranged in such a manner as to contact as directly as possible with the metals to be attracted and held thereby.

It is obvious that the whole hand might be formed of magnetized material by making the magnet in such form.

The magnets C may be made in any desired form and held in any other manner found most convenient in the process of manufacturing the dolls.

Having thus described my invention, I claim as new:

1. A doll of the character described having hands, and magnets secured in the palm portions of hands, said magnets being positioned to attract and hold magnetic material to the said palm portions.

2. A doll of the character described having hands formed of plastic material and a magnet embedded within the palm portion of each hand and adapted to attract and hold magnetic materials against the said palm portions.

3. A doll of the character described having hands, and a magnet firmly secured beneath the surface of the palm portion of each hand, the surface of said magnet adjacent the palm portion being covered to hide the magnet from view, said magnets being positioned to attract and hold magnetic materials to said palm portions.

Signed at New York, in the county of New York and State of New York, this 6th day of July, A. D. 1922.

GEORGE H. PARSONS.
